United States Patent Office

Des. 196,346
Patented Sept. 17, 1963

196,346

CLOTHING DISPLAY RACK OR SIMILAR ARTICLE

Daniel E. Gelles, 115 Ocean Ave., Brooklyn, N.Y.

Filed Feb. 21, 1963, Ser. No. 73,669

Term of patent 14 years

(Cl. D80—8)

FIG. 1

FIGURE 1 is a front perspective view of a clothing display rack or similar article, showing my new design; and

I claim:

The ornamental design for a clothing display rack or similar article, substantially as shown.
